TAPE PERFORATOR

James A. Spencer, Teaneck, N. J., assignor to
Radio Corporation of America, a corporation
of Delaware

Application May 14, 1938, Serial No. 207,884

6 Claims. (Cl. 164—112)

This invention relates to tape perforators as used preliminary to automatic printing telegraph code transmission. The invention has more particularly to do with apparatus which is adapted to perforate a transmitting tape in a suitable manner for use in a so-called 7-unit code system. In such a system the code combinations are of equal length and preferably the number of marking elements is uniform throughout the entire range of code combinations. In U. S. Patent No. 2,183,147, granted December 12, 1939, to John B. Moore and Richard E. Mathes, a code system is shown having a uniformity in the number of marking elements.

The reason for maintaining uniformity in the number of marking impulses in a signal, and hence the same uniformity in the number of perforations arranged transversely of the tape, is that this system lends itself to error detection at the receiving end. A receiving printer has been constructed which properly responds to uniform length code signals only when the number of marking elements of the signal is normal. Any abnormality in the signal reception incident to the introduction of static impulses or to the dropping out of impulses for any reason results in the actuation of an error indicating type bar in place of the type bar for the intended character.

It is an object of my invention to provide a keyboard-operated tape perforator which will at all times operate to perforate in the tape a fixed number of holes representative of the marking elements of a uniform length code signal.

It is another object of my invention to provide certain modifications and improvements of a keyboard tape perforator of any one of a number of well known types such that 7-unit code signals may be set up in the form of perforations for determining the characteristics of a uniform length code signal having a total of seven marking and spacing elements.

The invention will be illustrated and described hereinafter by reference to the accompanying drawing, in which

Figure 1 shows schematically and in perspective a few of the mechanical elements which in combination serve to link the keys of a manual keyboard to the punches within the punch block of a perforator;

Figs. 2, 3 and 4 show, respectively, different arrangements of notched code selector members such as may be attached to different keybars of a keyboard for actuating the punch control mechanism; and

Fig. 5 shows illustratively a piece of perforated

tape bearing perforations representative of the various code combinations to be used for the alphabet, figures, other characters and functional signals.

The embodiment of my invention as herein illustrated and described should be understood as merely illustrative since the invention itself is adaptable to other types of tape perforators. The specific form of perforator in which the invention is herein exemplified is well known in the art and has been described in a book entitled "Printing Telegraph Systems and Mechanisms" by H. H. Harrison, published by Longmans, Green & Company. On page 167 of this book is a brief description of a similar known keyboard perforator, reference being therein made to Fig. 165 on page 166. That was a perforator of the so-called "Morkrum" system. The apparatus with certain refinements of construction is now manufactured by the Teletype Corporation.

My improvements will now be described in detail.

Referring to Fig. 1, I show therein a keybar 10 which is only one, of course, of the entire group of keybars of the keyboard. This keybar is pivoted at 11 and carries a code selector comb 12 which may be affixed thereto in any suitable manner, as, for example, by rivets 13. The selector comb may, however, be welded on, if desired; or in certain instances it might be formed integrally with the keybar. Beneath the comb 12 is an arrangement of loop bails P and 1 to 7 inclusive. The bail P is actuated by each and every key and has the function of closing the contacts of a switch for electromagnetically driving the punch hammer and the tape feed device. The remaining loop bails 1 to 7 inclusive serve when they are actuated for disengaging their respective punches so that no corresponding holes are punched in the tape upon actuation of the punch hammer.

The mechanical linkages between the bails and the punches include upwardly projecting lever arms 14 which are integral with the bails 1 to 7. The upper end of each lever arm 14 is notched to form a yoke for carrying the tip end of a bell crank 15. Seven of these bell cranks 15 are mounted one over the other on a vertical pivot post 16. The forward ends of the bell cranks are pivotally connected at 17 to control arms 18. These control arms extend within the assembly consisting of die and stripper plates, punch block, guide plate, shredder, and shredder wearing strip shown generally at 19. The details of construc-

tion of this assembly are not herein described since they are well known in the art.

Upon each depression of a key, contacts associated with the bail P are closed for energizing a magnet (not shown). This magnet serves to drive the punch hammer forwardly into engagement with each of the tips of the members 18 which have not been withdrawn. The members 18 serve, therefore, to transmit the blow of the punch hammer to the individual punches for perforating the selected permutation of holes in any three of seven positions arranged transversely of the tape. Referring to these positions by number from the top down, it will be noted that three of them stand above and four below a preferably smaller punch hole 20 the purpose of which is to punch a continuous row of sprocket feed holes in the tape. The punch which perforates the sprocket feed holes in the tape responds always to the actuation of the punch hammer and the latter responds to the actuation of the bail P by each of the keys.

According to the practice of the prior art, the tape is fed past the punches one step at a time in response to each return stroke action of the punch hammer. The tape feed device is not new and has not, therefore, been shown herein.

In order that the improvements comprehended in my invention may be better understood, I have shown by way of example, three of the selector combs 12 in the three Figures, 2, 3 and 4, respectively, where each of these combs is adapted for use in punching a permutation of three holes in the tape indicative of the letter or character to be transmitted. In Fig. 2 the code signal for the letter "E" is represented by a notched formation in positions 4, 5 and 6. In Fig. 3 the letter "Z" is symbolized by a notched comb wherein the notches occur in positions 1, 6 and 7. In Fig. 4 the notches of the comb 12 represent the letter "F" by being located in positions 1, 4 and 6.

The remaining permutations to be embodied in the notched combs 12 , which are attached to the keys 10 , may be readily understood by reference to Fig. 5. Here there is shown a length of tape which has been perforated with all the different code combinations required for transmitting the alphabet, the figures, the usual punctuation marks and other characters shown on an ordinary typewriter keyboard and certain functional signals, which are required especially in telegraph typewriter systems. These functional signals usually include a letter-shift signal, a figure-shift signal, a space and a bell. The receiving printer is adapted to ring a bell in response to the reception of a certain code signal which must always follow the figure shift signal. The bell signal may correspond with that of letter "S," or letter "J," if preferred.

In the operation of my invention a message to be transmitted is perforated on the tape by ordinary manipulation of the keys of the keyboard. It will be noted, however, that each and every key, except the blank key, serves to punch three code designating holes, no more, no less. The fourth hole which is very slightly offset from the center line of the code designating holes is merely a sprocket feed hole. This sprocket feed hole is punched not only in response to the actuation of every character key, but also by the blank key. Consequently the selector comb 12 which is attached to the blank key has no notches therein. In the absence of notches the punch hammer magnet and the tape feed devices are actuated, but no code designating holes are

punched. This blank key can be used for feeding out a certain length of tape sufficient so that, when the message-perforated portion of the tape is torn off, a reasonable length of blank tape will remain beyond the message perforations. Another device for punching the feed holes while feeding blank tape is also embodied in the conventional perforator and is more rapid in operation than the single-space action of the blank key. Such a device, however, is not new and has not been shown.

It will be understood by those skilled in the art that various modifications of my invention may be adopted without departing from the spirit thereof. The scope of the invention itself is, therefore, defined by the claims to follow.

I claim:

1. In a keyboard-operated tape perforator, a plurality of key bars sufficient in number to individually represent the letters of the alphabet and other characters, at least eight bails underlying the key bars, tape punching and feeding mechanism operable under control of one of said bails by depression of any key, and means including a selector comb mounted on each key bar and each permutationally and distinctively notched to avoid engagement with exactly three of the bails appropriate to selected positions in which code-designating holes are to be punched, said means serving also to depress the remaining bails in response to a key depression, whereby blanks are left in the tape in non-selected positions.

2. A keyboard operated tape perforator having means for punching seven rows of holes for designating the elemental characteristics of uniform length code signals, means for punching still another row of holes for tape feeding requirements, a set of key bars, a selector comb mounted on each key bar, and means including bails underlying and engaging with the combs for communicating the motion of a given key to said punching means, said selector combs being further characterized in that each one is suitably notched for avoidance of engagement with exactly three of said bails.

3. A set of selector combs for attachment individually to the key bars of a telegraph sending-tape perforator, in combination with eight underlying bails, a group of code-element punches, means operable by one of the bails for perforating and feeding the tape, and means simultaneously operable by any four of the remaining seven bails for preventing the actuation of corresponding code-element punches, each of said selector combs being adapted to engage with a predetermined and distinctive combination of precisely five of said bails.

4. In a telegraph sending tape perforator, a keyboard having a plurality of key bars for selecting different code combinations to be punched in the tape, thereby to characterize a desired uniform length code signal, and a selector comb mounted on each of said key bars, each of said combs being conformed to a pattern whereby a fixed number of not less than three holes is punched in response to any key manipulation and said number of holes bears an unequal ratio to the number of unpunched code-element positions.

5. A device in accordance with claim 4 and comprising a power bail and a plurality of code determining bails, each cooperatively disposed with respect to different groups of selector combs, means under control of the power bail for caus-

ing a sprocket feed hole to be punched, and an additional key bar having a selector comb mounted thereon, the last said comb being engageable with all of the bails.

5 6. The method of producing a telegraph transmitting tape by means of a keyboard perforator, which comprises causing each character key de-

pression to perforate an appropriate combination of code-element holes in a fixed number of positions arranged transversely of the tape, and causing the selected positions to be at least three in number and to be maintained in a constant 5 minority ratio to the available positions.

JAMES A. SPENCER.
